UNITED STATES PATENT OFFICE.

JOSEPH F. MONTINE, OF NEVINVILLE, IOWA.

OVERHEAD TRANSPORTATION SYSTEM.

1,246,139.

Specification of Letters Patent.

Patented Nov. 13, 1917.

Application filed November 23, 1916. Serial No. 133,072.

To all whom it may concern:

Be it known that I, JOSEPH F. MONTINE, a citizen of the United States, residing at Nevinville, in the county of Adams and State of Iowa, have invented new and useful Improvements in Overhead Transportation Systems, of which the following is a specification.

This invention relates to apparatus for collecting and delivering mail matter, parcels, merchandise, etc., along a route, the same being characterized by an elevated track on which is mounted for travel a truck or carriage which supports the receptacle in which the goods to be delivered and collected are carried. The truck is propelled by an electric motor.

The invention relates more particularly to the motor control, its object being to provide an automatic switch which opens the motor circuit when the truck reaches a station or place of collection and delivery. A means is also provided for reversing the motor so that the truck may run back along the route without turning it around.

The invention also has for its object to provide novel and improved means for supporting the overhead cable on which the truck travels and also the trolley wire from which the electric current for the motor is obtained.

In order that the invention may be better understood, reference is had to the accompanying drawings forming a part of this specification, and in said drawings—

Figure 1 is a side elevation of the apparatus, partly diagrammatic;

Fig. 2 is a plan view, partly in section and partly diagrammatic, showing the motor controlling means;

Fig. 3 is an end view, partly in section, of the motor controlling means;

Fig. 4 is a cross-section on the line 4—4 of Fig. 1;

Fig. 5 is a side view from the line 5—5 of Fig. 4;

Fig. 6 is a cross-section on the line 6—6 of Fig. 2, with certain parts broken away, and

Fig. 7 is a cross-section on the line 7—7 of Fig. 5.

Referring specifically to the drawings, the overhead track which supports the apparatus in running position is a cable 13 supported at suitable intervals by being partly embedded in a block 17 reinforced

by side plates 18 having beveled ends 19 to give a smooth support as the wheels 12 of the truck or carriage roll over the same. The parts 17 and 18 are mounted between the outer ends of a pair of channel bars 20 extending horizontally from opposite sides of a pole 16 mounted alongside the track and fixed to said pole. These channel bars form bracket arms, and their channels face outwardly, the parts 17 and 18 having bottom portions 21 and 22 fitting between the inner faces of the bars, and the bottom portion 21 of the part 17 being secured to the bars by rivets 23. As shown in Fig. 5, the parts 17 and 18 also seat on top of the bars 20 and extend well beyond the same, so that a wide support is had, and twisting action is effectually prevented.

Back of the cable support hereinbefore described two braces 24 extend diagonally between the pole 16 and the bars 20, and immediately to the rear of said braces the bars are connected by a webbed cross bar 25 secured to the bars 20 by rivets 26.

The cross member 25 is enlarged intermediate its ends to form a vertically positioned hollow boss or sleeve 27 which serves to support an upstanding post 28 by means of a rain-shedding hood 29, insulating washers 30 and binding nuts 31, as shown in Fig. 6. The post 28 rises to the height of an overhead conductor or trolley wire 15 and carries a support 33 for the latter. The washers 30 insulate the trolley wire support from the cable support.

On the cable 13 travels an electric-motor driven truck or carriage from which is suspended a receptacle 10 carrying the merchandise, mail matter, etc., to be transported. The truck is a suitable frame having uprights 34 at its ends, which latter have bearings supporting the axles of the wheels 12. The truck frame is also provided with a trolley pole 14 carrying a current collecting wheel 14^a which runs on the trolley wire 15. The electric motor which propels the truck is shown at 11.

One of the uprights 34 supports a vertical corner plate 35 braced by a backing plate 36 and secured by rivets 37. This corner plate has a broad horizontal web 38 between its upper and lower ends, said web being braced by an integral flange 39 extending diagonally between the same and the corner 110 of the plate 35. These parts form a supporting bracket, and the outer end of the web 38

has a circular boss 40 through which passes a vertical pin 41 on which latter is mounted the hub 42 of a star wheel having six radial arms, three alternating ones 46 of said arms being positioned at a lower level than the other three denoted by the reference character 47. The hub 42 is hollow to house a spring 44 coiled around the pin 41 and held by a nut 45 provided with a washer 45^a. The star wheel is free to turn on the pin 41 but it can be rotated only by being forced, the spring 44 holding it normally stationary. Each arm 47 has a bevel-edged protuberance 47^a on its top, spaced the same distance from the center of the star wheel.

On each side of the flange 39, and integral with the web 38, are two frusto-conical members 48 having vertical axes and being open at the top and bottom, with a transverse partition 49 on the inside. Each member 48 forms an insulating unit for a vertical pin 50 axially positioned therein and supported by the partition 49 and an assembly of insulating washers the same as the device in Fig. 6. Above the partition 49, each member 48 may be packed with an insulating compound to prevent the entry of water. The lower end of the pin 50 is positioned to come in contact with any of the protuberances 47^a that may approach it when the star wheel is rotated. It will be noted in Fig. 2 that the pins 50 are set sixty degrees apart to correspond to the spacing of the arms 46 and 47. Thus, when one pin 50 is touched by a protuberance 47^a, the other pin 50 remains free, and vice versa. The spring 44 also assures proper contact between the pins and the protuberances.

The star wheel and coöperating parts just described constitute a switch which controls the motor 11 in a manner to be presently described.

The following device is provided for actuating the star wheel or switch assembly:

On a pole 18^a positioned alongside the track is fastened a socket member 53 having a base 52 through which pass fasteners 52^a which secure said member to the pole. In the socket is fixed, by a set screw 54, a horizontal bracket arm 51 having a downturned outer end 55, on which latter is adjustably mounted and secured by a set screw 56^a, a collar 56 carrying an elongated, hood-like member 57 open at one end and closed at the other end. Above its open end, the hood has a boss 58 through which a pin 59 passes, said pin carrying a block 60 which is free to turn on the pin. One side of the block 60 carries a wing 61 which is in the path of the arms 46 and 47 of the star wheel, and back of the wing, the block has a finger 62 projecting into the hood 57. To the outer end of the finger 62 is fixed one end of a coiled spring 63 housed in and anchored at its other end 65 to the hood. It will be seen that the wing

61 serves as an abutment to turn the star wheel when it is struck by the arms 46 of the latter. The spring 63 normally holds the wing projecting obliquely into the path of the star wheel arms 46, and as the wing is pivoted it is free to swing back to the dotted line position in Fig. 2 until it engages a stop 64 on the boss 58. A swing through a greater arc in the opposite direction is however possible as there is no stop to oppose such swing. The spring 63 always restores the wing to its normal position.

The wiring of the switch mechanism is as follows:

Conductors 65 and 66 lead from the contact pins 50 to the base of a double pole switch 67 located at any convenient and sheltered place on the receptacle 10. The conductors 65 and 66 are connected, respectively, to contacts 68 and 69 on one side of the switch. From a contact 68^a alongside the contact 68 a conductor 70 passes to one of the terminals of the motor 11, and from a contact 69^a alongside the contact 69 a conductor 73 passes to the other terminal of the motor. The first-mentioned motor terminal is also connected by a conductor 70^a to the contact 71 of a single pole switch 72, the other contact 71^a of said switch being connected to the second motor terminal by a conductor 73^a. From the switch arm or lever 72 a conductor 74 connects with the current collector 14^a.

The operating of the motor-controlling mechanism may be summarized as follows:

Referring to Fig. 2, one of the contacts 47^a is engaging the pin 50 from which the conductor 65 leads. The blades of the switch 67 are connecting the contacts 68 and 68^a, and the switch lever 72 is on the contact 71^a. With the parts in this position, the motor is running to propel the truck, the circuit being from current collector 14^a to conductor 74, switch 72, conductor 73^a, motor 11, conductor 70, switch 67, conductor 65, pin 50, contact 47^a, and thence to the truck frame, the return being through the cable 13 on which the truck runs. When the truck arrives at the stopping place, the abutment 61 being here located, the switch mechanism is operated to break the motor circuit. This is done by the forwardly extending arm 46 shown in Fig. 2 striking the abutment 61, whereupon the star wheel is turned to engage the aforementioned contact 47^a from the pin 50, thereby breaking the motor circuit. To start the motor, the star wheel is turned manually to again bring one of the contacts 47^a on the pin 50, in which position of the star wheel one of the arms 46 is standing straight out, as shown in Fig. 2, to be intercepted by the abutment 61 at the next stopping place or station. It will therefore be seen that alternate ones of the star wheel arms are switch arms and the other arms are switch

actuating arms, the arms 47 being the switch arms and the arms 46 being the actuating arms. When the active arm 46 strikes the abutment 61 the latter swings back, as shown 5 dotted, until it engages the stop 64, and the star wheel is then turned far enough to take the active switch arm 47 away from the contact pin 50. To reverse the motor it is necessary only to throw the switch 67 so that 10 the contacts 69 and 69^a are bridged, and also to throw the switch lever 72 over on the contact 71. The star wheel is now turned to bring one of the contacts 47^a against the pin 50 to which the conductor 66 is connected. 15 The motor now runs in a reverse direction, the circuit being from current collector 14^a to conductor 74, switch 72, conductor 70^a, motor 11, conductor 73, switch 67, conductor 66, pin 50, and contact 47^a. Two sets 20 of switch tripping wings 61 will be provided, one set acting when the carriage moves in one direction, and the other set when the carriage is running in the opposite direction.

25 I claim:—

1. The combination of a track, an electric-motor driven truck mounted for travel on said track, a pair of switch contacts carried by the truck to which contacts the motor 30 circuit is connected, a reversing switch mechanism for the motor circuit, a rotatable member carried by the truck and having radial arms, alternate ones of said arms having contacts adapted to engage the aforesaid 35 switch contacts and the other arms being the actuating means of the rotatable member, the spacing of the switch contacts corresponding to the spacing of the arms, and an abutment mounted alongside the track in the path of 40 the aforesaid actuating arms.

2. The combination of a track, an electric-motor driven truck mounted for travel on said track, a pair of switch contacts carried by the truck to which contacts the motor circuit 45 is connected, a reversing switch mechanism for the motor circuit, a rotatable member carried by the truck and having radial arms, alternate ones of said arms having contacts adapted to engage the aforesaid 50 switch contacts and the other arms being the

actuating means of the rotatable member and located in a different vertical plane from that of the first-mentioned arms, the spacing of the switch contacts corresponding to the spacing of the arms, and an abutment mounted alongside the track in the path of the aforesaid actuating arms. 55

3. The combination of a track, an electric-motor driven truck mounted for travel on said track, a pair of switch contacts carried by the truck to which contacts the motor circuit is connected, a reversing switch mechanism for the motor circuit, a rotatable member carried by the truck and comprising a hub having radial arms, alternate ones of 60 said arms having contacts adapted to engage the aforesaid switch contacts and the other arms being the actuating means of the rotatable member, the spacing of the switch contacts corresponding to the spacing of the arms, a pivot pin passing through the hub, 65 said hub having a bottom opening, a spring seating in said opening and coiled around the pivot, an abutment on the pivot pin, between which abutment and the hub the 70 spring is located, a bracket arm on the truck carrying the pivot pin, and an abutment mounted alongside the track in the path of the aforesaid actuating arms. 75

4. The combination of a track, an electric-motor driven truck mounted for travel on said track, a pair of switch contacts to which the motor circuit is connected, a bracket arm on the truck and having tubular members provided with partitions carrying the 80 contacts, the same being housed in the members below the partitions, a reversing switch mechanism for the motor circuit, a rotatable member carried by the truck and having radial arms, alternate ones of said arms having contacts adapted to engage the aforesaid 85 switch contacts and the other arms being the actuating means of the rotatable member, the spacing of the switch contacts corresponding to the spacing of the arms, and an abutment mounted alongside the track in the path of the aforesaid actuating arms. 90 95

In testimony whereof I affix my signature.

JOSEPH F. MONTINE.
